UNITED STATES PATENT OFFICE.

CHARLES CLARENCE POOLE, OF EVANSTON, AND JAMES P. DIKE, OF CHICAGO, ILLINOIS, ASSIGNORS TO CHARLES H. BESLY, OF CHICAGO, ILLINOIS.

HOLDING DEVICE FOR INDEX-CARDS.

SPECIFICATION forming part of Letters Patent No. 783,758, dated February 28, 1905.

Application filed February 13, 1903. Serial No. 143,193.

To all whom it may concern:

Be it known that we, CHARLES CLARENCE POOLE, a resident of Evanston, and JAMES P. DIKE, a resident of Chicago, in the county of 5 Cook and State of Illinois, have invented certain new and useful Improvements in Holding Devices for Index-Cards; and we do hereby declare that the following is a full, clear, and exact description thereof, reference being had 10 to the accompanying drawings, and to the letters of reference marked thereon, which form a part of this specification.

This invention relates to improvements in holding devices for detachably holding or retaining in index drawers or cases index-cards, such as are used for indexing or reference.

The invention consists in the matters hereinafter set forth, and more particularly pointed out in the appended claims.

20 In the accompanying drawings, illustrating our invention, Figure 1 is a plan view of a drawer for index-cards embodying our invention. Fig. 2 is a central longitudinal section thereof. Fig. 3 is a cross-sectional view thereof, taken on line 3 3 of Fig. 1. Fig. 4 is a detail plan section taken on line 4 4 of Fig. 3. Fig. 5 is a fragmentary view of the lower edge of one of the index-cards to be placed within the holder or drawer, said figure illustrating the holding-notch in said index-card. Fig. 6 is a plan view showing a drawer for index-cards embodying a somewhat different form of device embodying the principal features of our invention. Fig. 7 is a cross-section taken on line 7 7 of Fig. 6. Fig. 8 is a detail plan section taken on line 8 8 of Fig. 7.

As illustrated in said drawings, A indicates the bottom wall of the drawer or receptacle, A' the front wall, and A² the rear wall thereof.

40 A³ A³ indicate the side walls of the receptacle.

B B indicate two holding-rod^s which extend horizontally and parallel with each other from front to rear of the drawer a short distance above the bottom thereof. Said rods are movable both endwise and laterally. Attached to the front wall A' of the drawer is a horizontal guide-plate C, and attached to the

rear wall is a like guide-plate D. Said guide-plates C and D extend inward from the walls 50 to which they are attached and are provided each with two oblique guide-slots c c, d d. The guide-slots in each plate are arranged at an angle to each other and inclined in opposite directions; but the slots in the two plates 55 are alike in inclination and arrangement. The holding rods or wires B B are provided at their forward and rear ends with vertical parts or studs b b', which extend downwardly through the oblique slots c c and d d, the said 60 rods B B being made of such length or the studs b b' being so located with respect to each other that when the said studs are engaged with the oblique slots c c and d d and both rods are moved forward in an endwise direction the studs at both ends of the rods will engage the forward or separated ends of both sets of said slots c c and d d, and when said rods are moved backward said studs will likewise engage the adjacent or rear ends of both 70 sets of slots.

Located in the forward part of the drawer is an actuating-lever E, which is arranged to swing in a vertical plane, is pivoted at one end to the bottom of the drawer near one side 75 of the same, and has its free end located beneath and closely adjacent to the forward guide-plate C. As herein shown, said lever is pivoted to the bottom of the drawer by means of a pivot stud or screw e. The free 80 end of the lever E is bent around the guide-plate C and is then directed upwardly to form a rigid standard E', located centrally over said guide-plate. Said standard E' is provided with a notch e' in its upper end, which notch 85 is engaged by the curved edge of a spirally-formed cam-plate F', attached to a horizontal rod F, which passes through the front wall A' of the drawer and is provided at its outer end with a knob F², by which said rod may 90 be turned and the cam-plate F' thereby actuated. Said cam-plate F' is so shaped that when the knob is partially turned its spirally-formed edge by its engagement with the notch in the standard E' will move the free end of 95 the lever E toward and from the front wall of

the drawer. Said lever is provided below the guide-plate C with a longitudinal slot e^2 , into which the depending ends or studs b on the rods B B project. Said studs b being engaged with the oblique slots in the guide-plates C and D and also with the longitudinal slot e^2 of the actuating-lever E, when the free end of said actuating-lever, in which the slot is formed, is moved toward and from the front 10 end of the drawer or in a direction endwise of the rods the actuating-lever will shift or move the rods endwise, and thus carry their studs b backwardly or forwardly in the oblique slots c d , with the effect of drawing said 15 rods together or spreading them apart, the rods being in the construction illustrated spread apart or separated when the ends of the rods are engaged with the forward parts of the slots c d and being brought together when 20 the rods are thrust rearwardly and their ends are brought into engagement with the rear ends of said slots c d .

The cards which are inserted into the drawer or case and which are to be engaged by the 25 holding-rod B B will be provided with notches in the lower surfaces of T form—such, for instance, as are indicated at J in Fig. 5, which shows the lower part of one of said cards provided with the slot j . Said cards are inserted 30 in the case or drawer when the holding-rod are drawn together, the rods passing through the narrow part of the slot j , and when the cards are in place the rods are spread apart and are thus engaged with the wider upper 35 part of the slot j , whereby the cards are prevented from accidentally slipping out of the drawer.

From the construction described it will be obvious that by turning the knob F² the holding-rod B B may be brought together, so that the index-cards may be placed in the drawer and the rods engaged with the slots in the lower edges thereof, and the rods may be then spread apart to engage the upper horizontal 45 part of the key-shaped slot in the said index-card.

For limiting the turning movement of the knob F² and the cam-plate F² a radial pin f is inserted through the rod F and a stop-pin f' 50 is inserted in the inner face of the drawer in position for contact with said radial pin. The radial pin f projects from both sides of the rod F and by contact of its opposite ends with the stop-pin f' prevents the cam from being 55 turned more than half of a complete rotation, the working edge of the cam-plate preferably being extended through somewhat more than a half-circle.

In Figs. 6 to 8 we have shown a somewhat 60 different form of construction in a device embodying the main feature of our invention. In this instance the drawer is made in the same manner as before described and is provided with guide-plates C and D at its front 65 and rear ends and holding rods or wires b b,

adapted to engage at their ends with oblique slots c c , d d in the said guide-plates in the same manner as before described. In this instance an actuating-lever E³ is arranged in the forward part of the drawer and is pivoted 70 at one end of the drawer and extends transversely across the same to the opposite side thereof. As shown in the drawings, said lever is pivoted to the bottom of the drawer by means of a screw e³, while its opposite or free 75 end is located in an opening a, formed in the opposite side wall of the drawer, the free end of the lever E³ being preferably turned upwardly to form an arm e⁴, which constitutes a finger-piece by which the lever may be readily 80 moved backward or forward. The portion of said lever E³ adjacent to the guide-plate C extends beneath and closely adjacent to said guide-plate. The swinging of the free end of the lever E³ has the effect of moving the central part of the arm, which is beneath the guide-plate C, horizontally toward or from the front wall of the drawer or in a direction 85 endwise of the holding-rod. In said lever E below the guide-plate is formed a longitudinal 90 slot e⁵, and the downturned ends of the holding-rod B B project through the said guide-slots c c into the slot e⁵, so the ends of the holding-rod engage both the oblique slots c c and the said longitudinal slot e⁵. As a result 95 of the construction described it is obvious that by movement of the lever E³ the holding-rod B B will be shifted backwardly and forwardly and that through the engagement of the downturned ends of said rods with the said guide-slots the forward movement of the lever will, 100 through its connection with the said holding-rod, have the effect of moving the same forwardly in the guide-slots c c and d d , with the result of spreading the rods bodily apart, 105 while maintaining them in a parallel relation, and, similarly, a backward movement of said lever E by shifting both of the rods backwardly in said guide-slots will have the effect of bringing them together. 110

We claim as our invention—

1. The combination, with a receptacle, of a holding device for index-cards or the like, comprising two endwise and laterally movable, parallel, holding-rod provided at their ends with vertical studs, stationary, horizontal guide-plates secured to the end walls of the receptacle above the bottom of the same and provided each with two oblique slots which in the two guide-plates are inclined in the same 115 direction and through which the studs on the rods extend, and an actuating-lever which is pivoted at one end to the receptacle and at its opposite end has sliding engagement with one of said guide-plates, said lever having in its 120 end which engages the guide-plate a slot arranged transversely with respect to the holding-rod and adapted for engagement with the studs on the adjacent ends of said rods.

2. The combination, with a receptacle, of a 125

holding device for index-cards and the like, comprising two endwise and laterally movable, parallel, holding-rods provided at their ends with vertical studs, stationary, horizontal guide-plates located at the ends of the receptacle above the bottom thereof and provided each with two oblique slots which in the two guide-plates are inclined in the same direction and through which said studs on the rods extend, an actuating-lever pivoted at one end thereof to the receptacle having at its free end a slot arranged transversely with respect to the rods and adapted for engagement with the studs on the rods at one end of the receptacle, said lever having sliding engagement at its free end with the adjacent guide-plate and being provided with an upwardly-extending standard, and a rotative rod extending through the end wall of the receptacle and provided with a spirally-formed cam-plate which engages the said standard on the actuating-lever.

15 3. The combination, with a receptacle, of a holding device for index-cards and the like comprising two endwise and laterally movable parallel holding-rods provided at their ends with vertical studs, stationary, horizontal

guide-plates at the ends of the receptacle provided each with two oblique slots which in the two guide-plates are inclined in the same direction and through which the studs on the rods extend, an actuating-lever pivoted at one end thereof to the receptacle having at its free end a slot arranged transversely with respect to the rods and adapted for engagement with the studs on the rods at one end of the receptacle, said lever having sliding engagement at its free end with the adjacent guide-plate and being provided with an upwardly-extending standard, and a rotative rod extending through the end wall of the receptacle and provided with a spirally-formed cam-plate which engages the said standard on the actuating-lever.

20 In testimony that we claim the foregoing as our invention we affix our signatures, in presence of two witnesses, this 23d day of January, A. D. 1903.
